UNITED STATES PATENT OFFICE.

JOHN THOMSON, OF NEW YORK, N. Y., ASSIGNOR TO NEPTUNE METER COMPANY, OF NEW YORK, N. Y., A CORPORATION OF NEW JERSEY.

WATER-METER.

SPECIFICATION forming part of Letters Patent No. 783,485, dated February 28, 1905.

Application filed October 19, 1903. Serial No. 177,621.

To all whom it may concern:

Be it known that I, JOHN THOMSON, a citizen of the United States, residing in the borough of Manhattan, in the city of New York, in the county and State of New York, have invented 5 certain new and useful Improvements in Water-Meters, of which the following is a specification.

This invention has particular relation to water-meters, and in the accompanying drawings, forming a part hereof, Figure 1 is a view, partly in elevation and partly in vertical section, of a water-meter embodying my invention. Fig. 2 is a bottom plan view of the meter shown in Fig. 1. Fig. 3 is a detail view of the bottom or inclosing head for the main casing. Fig. 4 is a detail view of the bracket or spider for supporting the internal disk-chamber casing. Fig. 5 is a view of the lower 15 portion of a water-meter of the general construction shown in Fig. 1, the upper part being broken away, partly in elevation and partly in vertical section, embodying a modification of certain parts. Fig. 6 is a detail 20 view of a modified form of the bracket or spider for supporting the internal disk-chamber casing; and Fig. 7 is a detail vertical sectional view, partly broken away, of the screw provided with weakened threads.

It is well known that water when frozen increases in volume and that the expansion due to the transformation is practically irresistible. The result is that when water freezes in a closed vessel the vessel will be likely to be 35 destroyed unless some provision is made to save the essential or operative parts thereof under the stress, as by providing some part designedly made to yield or break when the stress exceeds that which the part designed to 40 yield will normally withstand.

The meter shown in the accompanying drawings is a disk water-meter, and, referring to Figs. 1, 2, 3, and 4, A is the main or outer casing. B is the lower inclosing head or bottom thereof. C is the internal casing or disk-chamber, made in two parts and containing the nutating-disk. D is the spindle attached to the ball of the disk. E is the arm which is connected to the shaft, forming a part of the

registering mechanism located within the outer inclosing case A above the disk-chamber C, the registering mechanism not being shown. F is the hinged cover inclosing the dial and pointers. (Not shown.) G is the inlet-port, and H the outlet-port, of the meter, 55 and I is the usual screen for excluding from the meter foreign matter. The shape of the bottom B is preferably circular, although, as will be understood, the bottom may be of any other desired shape, and this bottom is firmly secured to the outer casing A by the bolts J and washers K and in a water-tight manner by means of the perpendicular upwardly-projecting annular flange L, which impinges upon the gasket M, and the overturned outwardly-projecting flange N of the main casing, forming the seat for the gasket. The bottom B has a central orifice or aperture O, which is spanned by a strip or bridge-piece P, made integral with the bottom, or which bridge-piece may 60 be a separate piece therefrom. The orifice O in the bottom is closed by the inclosing piece or plug R, which is securely held in position by the screw S, which screw passes into and through an opening T in the bridge-piece P, 65 and the joint between the plug R and the bottom B is rendered water-tight by means of the gasket V, with which the plug R impinges, holding it to its seat formed therefor in the bottom B, as clearly shown in Fig. 1. A 70 washer or gasket V' is also inserted under the head of the screw S. The bottom B is provided with feet f, as many in number as desired, three being shown in the drawings, (see Fig. 2,) and the meter in its normal position is 75 designed to stand on said feet, as shown in Fig. 1. In order to support the disk-chamber casing C and to hold it to its seat W on the inside of the main casing, a bracket or spider Y is provided, preferably of the construction shown 80 in Fig. 4. This bracket or spider is provided with a central opening Z, into which opening the inner end of the screw S passes for the purpose of holding the support centrally in 85 position. The support Y is formed with any desired number of radial arms a, four being 90 shown in Fig. 4, and these radial arms are resilient for the purpose to be presently ex- 95

plained. The position and arrangement of the several parts when in normal operative condition are shown in Fig. 1, and it will be seen that in the construction there shown the 5 radial arms *a* of the support *Y* extend nearly to the circumference of the bottom of the internal casing *C*, furnishing thereby a large support for the disk-chamber; but I desire it to be understood that my invention is not 10 limited to the particular construction of the resilient supporting member of the disk-chamber shown in the drawings and hereinbefore described, nor that the supporting member shall spread across the entire bottom of the 15 disk-chamber, the essential function of the supporting member being that it shall furnish an adequate support for the disk-chamber casing. The gasket *M* is not designed to, but it may, project inwardly over the flange 20 *L*; but if this gasket should project there-over the disk-chamber casing in that event would rest upon the gasket to a slight extent, as well as upon the supporting member. The bridge-piece *P* of the bottom *B* is provided on 25 its inner surface with a central stud *b*, upon which stud the support *Y* is rested and positioned there centrally by means of the end of the screw *S* passing through the opening *Z* in the support, as heretofore described. The 30 central opening *T* in the bridge-piece *P* is pro- 35 vided with a female thread, and the shank of the screw *S* is provided for a portion of its distance with a male thread, which engages with the female thread in the opening *T* of the bridge-piece *P*, as clearly shown in Fig. 1. The outer surface of the plug *R* is slightly 40 recessed or countersunk to receive the head of the screw, as also shown in Fig. 1. In order to save the operative parts of the meter from 45 destruction in the event the water within the meter should freeze, the shank of the screw *S* is weakened, preferably by forming a weakening-groove *c* in its shank between the head of the screw and the threaded portion of the 50 shank, as shown in Fig. 1, the screw being designed to yield or break at the weakened groove *c* under the expansive force of the freezing water, thus permitting the plug *R* to drop away from the bottom *B*, and thereby afford the requisite relief to the excessive interior pressure.

In practical use of the meter shown in Fig. 1 the upper portion of the outer inclosing case above the disk-chamber would contain water, 55 the lower portion of the outer inclosing case would contain water, including the space below the bottom of the disk-chamber surrounding the supporting-bracket, and the disk-chamber itself would contain water, and the space below the bridge-piece *P*, between it and the plug *R*, would also contain water. All of the 60 parts of the meter, including the weakened screw *S*, would be designed to withstand the ordinary pressures of service—such as hydrostatic head, water-ram, and the like; but

the weakened screw *S* would be designed to yield under excessive pressure, such as that due to the freezing of the contained water. It is of course not possible to definitely state in advance the exact manner of freezing or the 70 location within the meter where the freezing would first take place under all circumstances of service; but no matter where the freezing occurs or whether it proceeds progressively from all parts of the meter interior whenever 75 the pressure within the meter becomes greater than the meter is designed normally to withstand this excessive pressure will travel in the direction of least resistance—to wit, in the structure shown in the direction toward 80 the weakened screw *S* and will fracture such screw at its weakened point, as the grooved portion *c*, and thereby afford the requisite relief to the pressure. If, for example, the 85 entire body of the water within the meter should have frozen with the relief of pressure consequent upon the rupture of the weakened screw *S*, the disk-chamber casing will have been forced away from its seat *W* by the 90 pressure of the ice above it and the disk-chamber casing will also have separated into its two component parts at the line of separation *d* by the pressure of the ice within it, and the ice will flow through the orifice in the bottom *B* produced when the screw *S* has 95 ruptured and let the plug *R* drop away from the bottom *B* and the disk-chamber and the supporting-bracket will also move with the moving or flowing of the ice, and under some 100 circumstances a plug of ice will protrude through the orifice in the bottom. If the entire quantity of the water within the meter shall, however, not have become frozen, but yet the pressure be too great, then when the 105 weakened screw *S* breaks, permitting the plug *R* to fall away from the orifice, the water within the meter will run out of the orifice *O*, thus affording the requisite relief and permitting the ice to flow and accommodate itself 110 within the meter-casings.

In the construction shown in Fig. 1 before the pressure has become great enough to rupture the screw *S* should ice be formed above the disk or within the disk-chamber *C* in advance of the freezing of the water in the 115 space below the bottom of the disk-chamber the expansion due to such freezing within or above the disk-chamber will deflect the resilient arms *a* of the supporting-bracket *Y*, permitting the disk-chamber to separate and move 120 bodily downward with the movement of the ice. When the ice has melted within the disk-chamber casing and above it, the resilient arms *a* will retroact and unite again the two parts of the separable disk-chamber and move 125 the same bodily upward, restoring it to its seat.

In the construction of the various parts of the meter shown in Fig. 1 I prefer to make the outer inclosing casing or main case *A* of 130

composition metal which will possess a high degree of tenacity and flexibility, the disk-chamber casing C of bronze, the supporting-bracket Y of ductile composition or spring metal, the bottom B of cast-iron or low-grade brass, and the screw S of bronze composition or steel.

From the foregoing it will be observed that in the event of freezing none of the essential operative parts of the meter will be damaged, and the only consequence of such freezing will be to fracture the preweakened screw S, and in order to restore the meter to its operative condition again it will only be necessary to furnish a new screw S, remove the threaded portion of the shank of the broken screw from its socket, and reassemble the parts, securely uniting them together by the new screw in the manner hereinbefore explained.

I do not limit myself to any particular dimension or size of orifice in the bottom B, for it is obvious that the relative size of this orifice will depend in some measure upon the character of metals of which the several parts of the meter are composed. When the several parts are made of the metals hereinbefore referred to, I have found that the relative area of orifice shown in Fig. 1 is entirely adequate to afford the requisite relief.

Referring to Figs. 5, 6, and 7, the general arrangement of the parts heretofore described in connection with Figs. 1, 2, 3, and 4 are the same in the meter shown in Fig. 5, the parts in Figs. 5, 6, and 7 corresponding to the parts in Figs. 1, 2, 3, and 4, being similarly lettered. In the meter shown in Fig. 5 the internal casing of the chamber is supported by the supporting spider or bracket Y, provided with the radial arms a, and the parts are securely held together by the weakened screw S, as hereinbefore explained in connection with Figs. 1, 2, 3, and 4. The supporting member Y is also preferably made of ductile composition, and the radial arms a are each provided with an upwardly-extending flange g, upon which the chamber-casing immediately rests, as clearly shown in Fig. 5. The under side of the supporting-bracket Y is provided with a central recess h, into which fits the inner end of the screw S for the purpose of holding the supporting-bracket Y disposed centrally in position. While in the case of the meter shown in Fig. 1 the weakened screw S is provided with a weakening-groove c, in the meter shown in Fig. 5 the screw is weakened by weakening the threads preferably in the manner as shown in Fig. 7, the consequence being that when the pressure within the meter becomes greater than the screw is normally designed to withstand the threads on the screw S will be stripped therefrom, the thread of the socket in the bridge-piece P remaining intact, thereby permitting the plug R to fall away and afford the requisite relief, as here-

inbefore explained in connection with the meter shown in Figs. 1, 2, 3, and 4. All that will be necessary to do in order to restore the meter to its normal operative condition will be to reassemble the parts and securely unite them together by means of a new screw 70 whose thread is weakened, as just explained.

What I have heretofore stated with reference to the area of the orifice in the bottom B in connection with the meter shown in Fig. 1 is applicable to the meter shown in Fig. 5. 75

As stated before, this invention has particular relation to water-meters and was devised primarily for use in connection with water-meters; but I do not limit my invention for use in connection with water-meters *per se*, for my invention may be applied to other structures, and therefore in the claims hereinafter following, while I claim my invention as applied to water-meters, yet I desire it to be understood that I use the term "water-meter" to include not only water-meters *per se*, but all analogous and other structures to which my invention may be applied. 80 85

What I claim as my invention is—

1. In a water-meter the combination with a main casing, of an internal casing, an inclosing head for the main casing, an orifice in said inclosing head, a bridge-piece on said inclosing head and spanning the orifice therein, means to close said orifice, a screw to unite 90 said closing means to said bridge, said screw being adapted to yield under excessive interior pressure, substantially as and for the purpose set forth.

2. In a water-meter the combination with a main casing, of an internal casing, an inclosing head for the main casing, an orifice in said inclosing head, a bridge-piece on said inclosing head and spanning the orifice therein, means to support the internal casing resting 100 upon said inclosing head, means to close the orifice in said inclosing head, and a screw to unite 105 said closing means to said inclosing head, said screw being adapted to yield under excessive interior pressure, substantially as 110 and for the purpose set forth.

3. In a water-meter the combination with a main casing, of an internal casing, an inclosing head for the main casing, an orifice in said inclosing head, a bridge-piece on said inclosing head spanning said orifice, a support for the internal casing resting upon said bridge-piece, a plug to close said orifice and a weakened screw to unite said plug to said bridge-piece, the inner end of said screw engaging with 115 and furnishing a centering for the support for the internal casing, said screw being adapted to yield under excessive interior pressure, substantially as and for the purpose set forth.

4. In a water-meter the combination with a main casing, of an internal casing, an inclosing head for the main casing, an orifice in said inclosing head, a bridge on said inclosing head 120 125

and spanning said orifice, a support for the disk-chamber resting upon said bridge, a plug to close the orifice in said inclosing head, and means to unite said plug to said bridge, said means being adapted to yield under excessive interior pressure, substantially as and for the purpose set forth.

This specification signed and witnessed this 5th day of October, A. D. 1903.

JOHN THOMSON.

In presence of—

ALFRED W. KIDDLE,
A. N. JESBERA.
